UNITED STATES PATENT OFFICE.

LOUIS BLUMENTHAL, OF BROOKLYN, NEW YORK.

SNAP-FASTENER.

1,184,413.

Specification of Letters Patent. Patented May 23, 1916.

Application filed January 13, 1916. Serial No. 71,876.

To all whom it may concern:

Be it known that I, LOUIS BLUMENTHAL, a citizen of the United States, residing at Brooklyn, county of Kings, and State of New York, have invented new and useful 5 Improvements in Snap-Fasteners, of which the following is a specification.

This invention relates to a device for securing the opening of a garment which can 10 readily be attached and cannot accidentally become disengaged when in action.

The invention comprehends a plurality of 15 spring loop members projecting outwardly from a base member, and a yoke bar adapted to coat with the members.

The essential object of the invention is to provide a space between the loop members so that when it is desired to have the yoke bar connect with the loops it can be inserted 20 in the space to spread the loops. When the bar is pressed the entire distance into the opening the loops will contract by reason of their inherent resiliency and thus positively lock the yoke bar in place.

25 The device is designed to provide means for preventing the yoke bar from laterally shifting after it is pushed into place between the loops.

The invention is more fully described in 30 the following specification and claims and illustrated in the accompanying drawing in which:

Figure 1 represents a front view showing the device attached to a garment. Fig. 2 35 is a side view of a yoke bar. Fig. 3 is a front view of a spring loop member showing the yoke bar snapped in place. Fig. 4 is a plan view of the same.

In this drawing is shown a snap keeper 40 preferably constructed of a single length of spring wire having a pair of eyes *a* formed at adjacent ends of the wire. These eyes serve to firmly attach the device by means of stitches *b* to the flap of a garment *c* as indicated in Fig. 1. A pair of loop members *d* are formed by convoluting the wire on each side of an opening *e* at the central portion of the device. The loops are joined together by a contiguous base member *f* 45 which is preferably concaved.

As indicated in Fig. 4 each loop has a plurality of convolutions to form a double outwardly projecting loop one being diametrically opposite and axially adjacent the other. 50 There are thus two pairs of loops one pair *d* being joined together by the base mem-

ber *f* while the other pair *d'* are united to the eyes *a* by branch wires *g* extending from the lower portions of the loops.

The yoke connection includes a bar provided with a concaved central member *h* and having convexed side portions *i* which are united to a pair of oppositely located eyes *j* by the upward extensions *k*. The yoke is formed of a single piece of wire and the eyes are for the purpose of attaching the yoke by sewing to the garment as shown at *m* in Fig. 1. It will be seen that when the yoke member is placed in alinement or register with the space between the outwardly projecting loops and pressed home the central concaved portion will rest on the base member *f* with the protruding convexed portions *i* forming stops on each side of the base to prevent lateral play of the yoke. In this connection it should be said that when the yoke bar is pressed into the opening until it reaches the axis of the loops it will compress them, hence widening the opening. Then when the yoke bar is pushed farther into the opening the jaws of the loop will 75 spring together and the bar will snap onto the base member. In this position the yoke bar cannot be disconnected from between the jaws of the loops until they are again 80 snapped apart by the withdrawal of the yoke bar.

While I have shown and claimed this device as being made of wire, it will of course be understood that I do not limit myself to 90 this material and that the device may be made of any suitable material.

I claim:

1. A snap fastener comprising a base member, a plurality of spaced spring loops 95 projecting outwardly from the base, and means for fastening the device to an article; combined with a yoke member adapted for insertion between the loop members.

2. In a snap fastener the combination 100 with a pair of outwardly projecting spring loops formed of wire, eyes extending from the lower portion of the loops and including a base member to join the loops, of a yoke member adapted for insertion between 105 the loops to coat with the base, and means for preventing lateral movement of the yoke member.

3. In a snap fastener the combination 110 with a pair of outwardly projecting spaced spring loops formed of wire, a base member joining the loops, including eyes located at

- adjacent ends of the wire, of a yoke member adapted for insertion between the loops to coact with the base, and means for preventing lateral movement of the yoke member.
- 5 4. In a snap fastener the combination with a pair of outwardly projecting spaced spring loops formed of wire, a base member joining the loops, including eyes located at adjacent ends of the wire, of a yoke member
- 10 adapted for insertion between the loops and having protuberances for preventing lateral movement and to coact with the base member.
- 15 5. In a snap fastener the combination with a pair of outwardly projecting spaced

spring loops formed of wire, a base member joining the loops, and eyes located at adjacent ends of the wire, of a yoke member adapted for insertion between the loops having upward extensions with eyes including 20 concaved and protuberant portions for preventing lateral movement and to coact with the base member.

In testimony whereof I have hereunto set my hand in the presence of two subscribing 25 witnesses.

LOUIS BLUMENTHAL.
